[57] CLAIM

The ornamental design for a picture frame, substantially as shown and described.

DESCRIPTION

FIG. 1 is a front elevational view of a picture frame showing my new design;

FIG. 2 is a rear elevational view thereof;

FIG. 3 is a side elevational view thereof, the side opposite being substantially a mirror image;

FIG. 4 is a perspective view of one side member of the design;

FIG. 5 is a front perspective view of the design shown in FIGS. 1 through 4; and,

FIG. 6 is a front perspective view of a corner insert member shown on an enlarged scale.
